UNITED STATES PATENT OFFICE.

FRED R. HARRIS, OF NEW YORK, N. Y., ASSIGNOR TO THE AMERICAN TOBACCO COMPANY, OF NEW YORK, N. Y., A CORPORATION OF NEW JERSEY.

BOX-MAKING MACHINE.

No. 846,410.

Specification of Letters Patent.

Patented March 5, 1907.

Application filed July 18, 1902. Serial No. 116,034.

To all whom it may concern:

Be it known that I, FRED R. HARRIS, a citizen of the United States, residing at New York, county of New York, and State of New York, have invented certain new and useful Improvements in Box-Making Machines, fully described and represented in the following specification and the accompanying drawings, forming a part of the same.

This invention relates to machines for making boxes from paper, pasteboard, or other suitable material.

The invention aims generally to improve the construction of such machines and to provide an efficient and convenient machine by which previously cut and scored blanks having a central portion, end, and side portions to be turned up and flats on the side or end portions to be turned in so as to lie in side of the end or side portions of the completed box shall be fed forward in succession, have paste applied at the proper places, and have their ends, sides, and flaps folded and pressed to shape the box and secure the pasted parts to the corresponding parts and by which the formed boxes are then delivered from the machine.

The invention includes improvements in means for feeding the blanks successively from a pile, pasting devices including means for automatically preventing the application of paste to parts of the machine when no blank is passing the paste-applying devices, means for folding the sides, ends, and flaps of the boxes, means for positioning the blanks with relation to the folding devices, and means for delivering the folded boxes.

A full understanding of the invention can best be given by a detailed description of a preferred construction embodying the various features thereof, and such description will now be given in connection with the accompanying drawings, showing such a preferred construction, in which—

Figure 1 is a general plan view of such a machine. Fig. 2 is a front view looking from the right in Fig. 1. Fig. 3 is a rear end view looking from the left in Fig. 1. Fig. 4 is a side view looking in the direction of the arrow 4 in Fig. 1. Fig. 5 is a side view looking in the direction of the arrow 5 in Fig. 1. Fig. 6 is a longitudinal sectional view taken on line 6 of Fig. 7. Fig. 7 is a transverse view taken on line 7 of Fig. 1. Fig. 8 is a plan

view of the blank-supporting and blank-feeding devices. Fig. 9 is a sectional view taken on line 9 of Fig. 8. Figs. 10, 11, and 12 are detail views of parts of the blank supporting and feeding devices. Fig. 13 is a detail sectional view of the blank-feeding devices, the pasting-roll, and devices for detecting the absence of a blank and for controlling the means for moving the pasting-roll to prevent the application of paste to the pressing-roll coöperating therewith. Fig. 14 is a similar view of such detecting and controlling devices, showing the detecting-finger in a different position. Fig. 15 is a plan view of such parts. Fig. 16 is a side view showing the pasting-roll and driving-gearing for the roller-bed over which the blanks pass to the folding devices and the feeding-rolls coöperating therewith. Figs. 17, 18, and 19 are detail views of the pushers for feeding the bottom blanks from the pile. Figs. 20, 21, and 22 are detail views of the cam for actuating the paste-transferring roll. Fig. 23 is a detail showing the lever and connections for returning the pasting-roll to pasting position. Figs. 24 to 28 are details of the front stop and support of the blank-holder. Fig. 29 is a plan view of the blank positioning and folding devices. Figs. 30 and 31 are details of one of the end blank-positioning guides. Fig. 32 is a detail of one of the rear blank-positioning pins. Fig. 33 is a side view of one of the end-folders and its operating connections. Fig. 34 is a detail view of the operating connections for one of the end-folders looking in the direction of the arrow 34 in Fig. 33. Fig. 35 is a section on line 35 of Fig. 33. Fig. 36 is a detail view of one of the flap-folders carried by the end-folders. Figs. 37 and 38 are respectively side and end views of the side-folders and their operating mechanism. Fig. 39 is a detail view of the devices for operating the reciprocating bottom support of the folding devices. Fig. 40 is a plan view taken below the folding devices, showing the operating-shafts and connections. Fig. 41 is a perspective view of the box-delivering mechanism. Fig. 42 shows the form of a blank before folding. Fig. 43 is a view of the blank as it appears when partially folded, showing the stay-flaps folded in advance of the side and end sections, so as to extend inside the ends of the box. Fig. 44 is a sectional view of the fold-

ing-plunger and support coöperating therewith and the end-folders and showing a blank being folded, the parts being in position just after the commencement of the folding operation. Fig. 45 is a similar view, but taken so as to show the side-folders. Fig. 46 is a view similar to Fig. 43, but showing the parts in position when the plunger and support have reached the lowest position of their movement and the box has been completely formed. Fig. 47 is a view showing the plunger, the coöperating support and the side-folders, and a completely-formed box, the parts being in position in which the plunger has been raised to its upper position and the box raised by the support into position to be carried from the folding devices by the delivering devices. Figs. 1 to 6 and 39 and 40 are drawn to the same scale. The remaining figures are drawn to larger scales.

Referring to the drawings, the various parts of the machine are supported by a frame 10. Journaled in suitable bearings in the frame is a driving-shaft 11, from which, by means of gears 12 and 13, is driven a shaft 14, carrying cams and gears by which the various operating parts of the machine are driven.

The blanks to be fed into the machine are placed in a pile in the blank-holder A, from which the bottom blanks are successively fed. The machine is intended to operate on blanks substantially of the form shown in Fig. 42, each having a central or bottom portion *a*, end sections *b*, side sections *c*, and stay-flaps *d*, extending from the ends of the side sections *c*. The end sections *b* and side sections *c* are separated from the bottom *a* by score-lines, and the stay-flaps *d* are separated from the side sections *c* by score-lines. The various parts of the holder A are supported by side brackets 20, extending forwardly from the main frame 10 and connected near their outer ends by a cross-rod 21. The blanks are centrally supported by supports 22, mounted as hereinafter described. Mounted on the upper rods 23 of the brackets 20 so as to be adjustable longitudinally thereof are two pairs of brackets 24, which carry cross-rods 25 and 26. Carried by the rod 25 so as to be adjustable longitudinally thereof and transversely of the machine are two pairs of brackets 27 27 and 28 28. Each of the brackets 27 carries a vertical rod 29, which rods form the front wall or boundary of the blank-holder and are vertically adjustable and carry at their lower ends supporting-fingers 36, which extend beneath the front edge of the bottom blank of the pile. Each of the brackets 28 carries a vertical rod 30. The rod 26 carries two pairs of brackets 31 31 and 32 32, adjustable on the rod 26 longitudinally thereof and transversely of the machine.

The brackets 31 31 carry rods extending longitudinally of the machine, on which are

adjustably mounted brackets 33, which carry vertical rods 34. Each of the brackets 32 carries a rod 35. The rods 35 35 and 34 34 and 30 30 form the side walls or boundaries of the blank-holder. The rods 34 34 and 35 35 are adjustable vertically in their respective brackets, and one or both pairs of said rods carry at their lower ends supporting-fingers 36, which extend beneath the edges of the bottom blank of the pile.

Mounted centrally of the path of blanks as they are fed from the pile is a gage-plate 40, which is vertically adjustable, as by means of an adjusting-screw 41, in a bracket 42, in which it is clamped by means of a clamping-screw 43. The gage-plate 40 is adjusted so as to leave a space between its lower edge and a support over which the blanks are fed of a width sufficient to permit only one blank to be advanced beneath the gage-plate at a time. For supporting the blanks as they are passed beneath the gage-plate there is preferably provided an adjustable supporting gage-block 45, having a flat surface beneath the gage-plate and downwardly inclined on the side toward the pile of blanks. This block 45 is, as shown, carried by a supporting-block 46, on which it is vertically adjustable and which block 46 is suitably mounted so as to be adjustable longitudinally of the machine, as shown. The block 45 also preferably carries a support and guide 47 for directing the edge of the blanks as they are fed forward between the plate 40 and block 45, which support 47 is preferably vertically adjustable, as shown.

Any suitable devices may be provided for successively engaging and feeding forward the bottom blanks from the holder. I prefer, however, to provide feeding means substantially as shown in the drawings and which will now be described. A slide 50 is mounted to reciprocate longitudinally of the machine between the brackets 33 33, and this slide is formed with a way in which is longitudinally adjustable a support 51, which carries a T-shaped bracket 52, adjustably secured thereto by means of screw-pins extending through vertical slots in uprights 53 on said support, so that the inclination of the bracket 52 may be varied as desired. Mounted in each end of the cross-bar of the bracket 52, so as to be longitudinally adjustable therein, is a rod 54, which carries at its rear or inner end a blank-pusher. A pusher of a preferred form is shown in detail in Figs. 17, 18, and 19 and consists of a block 55, having an inclined blank-engaging face 56 and an adjustable blank-engaging shoulder 57, said block being adjustably connected to a head 58, which is swiveled on the end of the rod 54, the connection between the swiveled head and the block 55 being such as to permit the block to be swung vertically on the head and secured in said position, as by means of the

screw 59. For providing the adjustable shoulder 57 the block 55 is preferably formed of the block proper and the shoulder-piece 60, extending within a recess in the block proper and adjusted against the tension of a spring 61 by means of a screw 62 to extend more or less above the surface of the block proper. I preferably provide two pushers, as shown, mounted to engage the edge of the bottom blank at some distance apart, as I am thereby enabled to insure the straight movement of the blank from the holder.

The slide 50 is reciprocated by means of a gear-segment 63, carried by a rock-shaft 64 and engaging a rack 65 on the slide. The shaft 64 is rocked by means of a connecting-rod 66, connecting at one end with an arm 67 on the shaft 64 and at the other end with a crank-disk on a shaft 68. The connecting-rod 66 preferably has an adjustable connection with the arm 67, as shown in Fig. 4, to permit the throw of the pushers 55 to be varied. The supports 22 are carried by a cross-piece 70 on the slide 50; so that as the pushers 55 move forward with the bottom blank the supports 22 will also move forward, and thus avoid friction between the supports and the bottom blank. The supports 22 are preferably in the form of longitudinally-arranged bars, as shown, and are preferably adjustable on the cross piece 70, as by means of the connection shown in detail in Figs. 10 and 11.

The various parts of the holder will be adjusted in accordance with the size and form of the blanks, and the blanks will lie in the holder in the position and with the various positioning-rods in contact with the edges of the blanks, as indicated by dotted lines in Fig. 8. The longitudinal and lateral adjustments of the various positioning-rods is secured by adjusting the cross-rods 25 and 26 and the various rod-carrying brackets. The rods 29, 34, and 35 are preferably adjustable so that their supporting-fingers will be in a plane slightly above the plane of the supports 22, so that the blanks as they lie in the holder will be raised slightly at the edges and the pressure on the supports 22, and consequently the pressure on the bottom blank of the blanks above, will be less than if all the supports lay in the same plane. The rods 34 and 35, further, the supporting-fingers 36 of which extend, respectively, beneath the end sections b and front stay-flaps d of the blanks as they lie in the holder, will be raised to position their supporting-fingers sufficiently above the supports 22 and with the fingers on the rods 35 above the fingers of the rods 34 so that as the bottom blank is advanced and its front flaps pass over the supporting-fingers of these rods the two rear stay-flaps will pass freely beneath the supporting-fingers of the rods 34, and the end sections b of the blank and the two rear stay-flaps will pass beneath the supporting-fingers

of the rods 35. This is important, as it avoids all chance of the edges of the end sections and of the second pair of stay-flaps coming in contact with the edges of these supporting-fingers and of the end sections coming in contact with the supporting-rods 35 when the end sections extend beyond the stay-flaps, as in the blank shown in Fig. 41. It should be further noted that by providing these supporting-fingers for supporting the main weight of the pile of blanks as the bottom blank is advanced by the pushers it is moved clear of these supporting-fingers after a very short movement and is thus relieved of the main part of the weight of the pile of blanks in the holder, and therefore is moved forward with but slight friction with the blank above it. At times it may be preferable to use supporting-fingers on only one pair of the rods 34 or 35, and they may be used on either the rods 34 or 35, or both, as required, according to the blanks being fed.

As the bottom blanks are successively advanced from the holder they enter between feeding-rolls 75 76, by which they are advanced to the pasting mechanism for receiving paste on the end sections b b. The pasting devices include a pasting-cylinder 77 and coacting pressure-roll 78. The pasting-cylinder is formed with longitudinally and transverse undercut grooves 79, and the pasting-plates 80 are held to the surface of the cylinder by means of clamps 81, adjustable in the grooves 79. This construction provides a convenient means for adjusting the pasting-plates on the surface of the cylinder and for permitting plates of different size to be used. The pasting-cylinder may be cut away, as shown in the drawings, for convenience in placing and moving the clamps 81, which are in the transverse or circumferential grooves. The pasting-cylinder and the roll 78 carry intermeshing gears 82 and 83 and are continuously driven from the cam-shaft 14 through gears 84, 85, 86, 87, and 88. Paste is applied to the pasting-cylinder by means of an oscillating transfer-roll 90, which oscillates to alternately engage the pasting-cylinder and fountain-roll 91 of the paste-fountain 92. The fountain and fountain-roll may be of any suitable construction, and the transfer-roll may be mounted and operated in any suitable manner. As here shown it is carried by arms extending from a rock-shaft 93, which shaft has an arm 94, carrying an antifriction-roll which is held by tension of a spring, as 95, in contact with a cam 96 on the shaft of the pasting-cylinder. The cam 96 is preferably adjustable circumferentially on the shaft of the pasting-cylinder and is preferably an extension-cam of suitable construction—such, for example, as shown in the detail views Figs. 20, 21, and 22—so that it may be adjusted to hold the transfer-roll in position to apply paste to the

pasting-plates for a longer or shorter time, according to the size of the plates.

To prevent application of paste to the roll 78 when the machine is in operation and no blank has been fed from the holder and between the pasting-cylinder and the roll 78, automatically-operating means are provided for raising the pasting-cylinder slightly if no blank is being fed to be pasted. For this purpose the pasting-cylinder is journaled eccentrically in rotary journal-blocks 100, which have arms 101, connected by rods 102 to arms 103 on a rock-shaft 104. Springs 105, bearing against collars 106 on the machine-frame and collars 107 adjustable on the rods 102, tend to move the rods 102 downward to rotate the journal-boxes 100 to raise the pasting-cylinder away from the roll 78. This movement of the rod 102 is normally prevented by means of a catch-arm 108, loosely mounted on a shaft 109 and engaging a stop-lug 110 on a collar on the shaft 104.

The shaft 109 is intermittently rocked by means of a cam 111 on the shaft 68, the shaft 109 having an arm 112, which carries an anti-friction-roll held in engagement with the cam 111 by means of a spring 113 on the shaft 109 and connected at one end with a collar on the shaft and at the other end with one of the shaft-supports. The shaft 109 will thus be rocked once for each movement of the blank-feeding devices. The arm 108, which is loose on the shaft 109, carries also a finger 114, and a finger 115, which is fast on the shaft 109, extends beneath the finger 114, but with a sufficient space between the fingers 114 and 115 so that if there is nothing interposed between them the finger 114 will not be moved by the movement of the finger 115 when the shaft 109 is rocked. By interposing a suitable movable block, however, between the fingers 114 and 115 the upward movement of the finger 115 when the shaft is rocked will cause an upward movement of the finger 114 and of the arm 108. Pivotally mounted on the upper end of a bracket 116 at a point just below the path of the blanks as they are fed to the pasting-roll is a detector-finger 117, extending forwardly from the point of pivotal connection to the bracket 116. The finger 117 has a downwardly-extending arm 118, which is pivotally connected with the upper end of a two-armed lever 119, which lever is pivoted on the bracket 116. A spring 120 tends to move the lever and arm 118 to throw the detector-finger upward. The lower end of the lever 119 is provided with a lug 121, so located that when the lever and detector-finger are permitted to move under the influence of the spring 120 the lug 121 will enter between the fingers 114 and 115, as shown in Fig. 14. It will be seen that when a blank is being fed past the detector-finger 117 to the

pasting-cylinder the detector-finger and the lever 119 will be held by the blank in the position shown in Fig. 13; but when no blank is being fed past the detector-finger the finger and lever 119 are free to move under the influence of the spring 120 to the position shown in Fig. 14. If now when the parts are in this position with the lug 121 between the fingers 114 and 115 the shaft 109 be rocked to move the finger 115 upward, then the finger 114 will be thrown upward and the arm 108 moved to carry its stop out of engagement with the lug 110. The shaft 104 being thus freed, the springs 105 will act to rock the journal-blocks 100, and thereby raise the pasting-cylinder away from the roll 78. The cam 111 for rocking the shaft 109 is so timed that the shaft will be rocked between the time that the front edge of a blank should reach the finger 117 and the time a blank should be in position beneath the pasting-cylinder for receiving paste, and the pasting-cylinder will thus be raised before the pasting-plates reach the roll 78. It will thus be seen that so long as the blanks are fed regularly the pasting-cylinder will remain in operative position; but if the feeding of the blanks be interrupted from any cause the pasting-cylinder will be automatically raised and the application of paste to the roll 78 thereby avoided.

To permit the lug 121 to move upward with the fingers 114 115, the lever 119 preferably has a slotted connection with the bracket 116 and with the arm 118, and a spring 122 is provided for normally holding the lever in its lower position, so that the lug 121 will be in a position to enter between the fingers 114 115. For returning the pasting-cylinder to operative position after it has been automatically raised, a hand-lever 123 is provided on the shaft 104. By throwing this lever in the direction of the arrow in Fig. 4 the shaft 104 will be rocked to return the pasting-cylinder to operative position and to bring the stop 110 into position to be engaged by the catch-arm 108. In addition to the spring 105 spring 124 may be provided on the shaft 104, as shown clearly in Fig. 7, such springs engaging at one end collars on the shaft and at the other parts of the shaft supports or bearings. The detector-finger 117 is preferably located so as to engage the blanks as they enter between the feed-rolls 75 and 76. It will thus engage the blank where it is moving uniformly in the same plane, and sureness of operation of the detector-finger is thus insured. The rolls 75 and 76 may be cut away or grooved to receive the finger 117, and the roll 75 is preferably formed by a series of disks, as shown.

For supporting the blanks as they are advanced to and beyond the pasting-cylinder a roller-bed, formed by a series of driven rolls 125, is preferably provided. As shown, these

rolls are geared to a shaft 127 by bevel-gears 128. The shaft 127 is driven from a gear 129 on the shaft of the roll 78 through an intermediate 130 and a pinion 131 on the shaft of one of the rolls 125. The roll 76 forms one of the series of rolls forming the roller-bed and is driven in the same manner as the rolls 125. The shaft of the roll 75 carries a gear meshing with a gear on the shaft of the roll 76 and is driven thereby. A feeding-roll 132 is provided to coact with one of the rolls 125, as shown in Fig. 6. This roll is driven from a pinion on the shaft of the roll 125 with which it coacts.

- 15 The blanks are advanced from the roller-bed to the folding devices by feeding-tapes 135, which pass around a roll 136, located just beyond the last of the rolls 125, and a roll 137, located beyond the folding devices. 20 (See Figs. 1, 13, and 29.) There are preferably two feeding-tapes 135, and the roll 136 is preferably formed of two separate rolls, mounted on and longitudinally adjustable on a shaft to provide for adjusting the position 25 of the tapes transversely for blanks of different sizes. The roll 136, and thereby the feeding-tapes 135, are driven at an accelerated speed by means of a belt 138, passing over a pulley on the main driving-shaft 11, Fig. 6, 30 and a feeding-roll 139 is preferably provided to coact with the roll 136. The blanks as they leave the roller-bed will thus be given an accelerated movement and will be brought more rapidly into position for the operation of the 35 folding devices, and a greater length of time will thus be available for the operation of the folding devices on successive blanks without unduly increasing the speed of the blank feeding and pasting devices.
- 40 The folding devices comprise a forming-plunger 150, a reciprocating bottom-support 151, side-folders 152, end-folders 153, and flap-folders 154, carried by the end-folders 153. The forming-plunger is carried by a rod 155, mounted to reciprocate vertically in bearings carried by a frame 156 and reciprocated by means of a cam 157 on the shaft 14. An arm 158, pivoted on a supporting-shaft 159, carries an antifriction-roll running in the 45 groove of the cam 157 and is connected, by means of a rod 160, with one arm of a bell-crank lever 161, the other arm of which is connected, by means of a rod 162, with an arm 163 on a rock-shaft 164, which has another 50 arm 165, connected by a link 166 with a cross-lead 167 on the rod 155 and preferably running in ways 168, supported by the frame 156. The bottom-support 151 is carried by a rod 170, mounted to reciprocate in suitable 55 bearings and actuated by a cam 171 on the shaft 14 through a swinging arm 172, having an antifriction-roll in position to be engaged by the cam and connected by a rod 173 with one arm of a bell-crank lever 174, the other 60 arm of which has a link connection with the rod 170.
- 65 The rod 160 preferably has an adjustable connection with the arm of the bell-crank lever 161, as indicated in Fig. 6, and is preferably formed by two parts connected, as by a turn-buckle, as shown, to permit the rod to be lengthened or shortened, and the rod 173 is preferably adjustably connected to the arm of the bell-crank lever 174, as indicated in Fig. 39, and formed of two parts, connected, as by a turn-buckle, to permit it to be lengthened or shortened. The movements and relative positions of the forming plunger and the support 151 may thus be varied and 70 adjusted as required.
- 75 The side-folders 152 are preferably formed by vertically-arranged plates carried by slides 175, mounted to move on guides 176 on the under side of a table 177. The table 177 has a central opening 178, into which the 80 plates forming the side-folders extend. The slides 175 are reciprocated toward and from each other by means of a cam 179 on the shaft 14, acting through a rod 180, having an antifriction-roll running in a cam-groove of 85 the cam 179 and guided by a pin 181 on a bracket 182. This rod 180 is connected to an arm 183 on a rock-shaft 184, supported in brackets 185, depending from the table 177. The rock-shaft 184 has a downwardly-extending arm 186, connected by a rod 187 with an upwardly-extending arm on a corresponding rock-shaft 188. The rock-shafts 184 and 188 are connected by arms 189 with the respective slides 175, so that by the 90 rocking of the shaft 184 by the rod 180 the slides 175 and the folders carried thereby will be caused to move alternately toward and from each other. The plates forming the folders 152 are adjustably connected to 95 the slides 175 by means of horizontally-extending supports 190, which carry the folder-plates and are connected to the slides by means of screws 191, extending through 100 slots in the supports. The end-folders 153 are also preferably formed of vertical plates and are carried each by a pair of horizontally-extending bars 200, mounted to slide on ways 201 on the under side of the table 177 and on opposite sides of the opening 178, 105 and the slides are reciprocated alternately toward and from each other each by means of a toggle 202, one arm of which is pivoted to the frame and the other arm connected to the bar 200 by means of trunnions extending 110 from a collar 203, through which the arm of the toggle extends and with which it is adjustably connected by means of lock-nuts, as shown in Figs. 32 and 34. Each of the toggles is operated by means of a rod 205, forked 115 to straddle the shaft 14 and carrying an antifriction roll, which is held in engagement with a cam 206 on the shaft 14 by means of a 120

spring 207. The rods 205 are preferably formed of two sections pivotally connected to bend in the direction of the length of the toggles and are of course pivotally connected to the toggles. Adjustable stops 208 are preferably provided to limit the breaking movement of the toggles by which the folders 153 are retracted.

The upper or feeding runs of the tapes 135 extend over the top of the table 177 and across the opening 178 and lie close to the top of the table. The upper edges of the plates forming the side-folders 152 are preferably substantially flush with the top of the table, and the upper edges of the plates forming the end-folders 153 are a little below the top of the table and the side-folders, so that the folding of the end sections of the blanks will not begin until after the beginning of the folding of the side sections, as hereinafter pointed out.

Each of the end-folding plates carries two stay-flap folders 154, which project a little above the end-folders and slightly inward from the face of the end-folders. These flap-folders, as shown in the drawings, are formed by the upward and backwardly turned end of slotted plates 210, which are carried by blocks 211, adjustably secured in undercut grooves formed in the upper edges of the folder-plates 153, so that the flap-folders may be adjusted longitudinally of the folder-plates 153 toward or away from each other. The plates 210 are secured to the blocks 211 by means of screws extending through the slots of the plates, thus permitting the flap-folders to be adjusted to project more or less beyond the face of the folding-plates 153. For securing greater rigidity of the plates 210 in the position to which they have been adjusted slotted bars 212 are preferably provided connecting the pairs of plates 210 beyond said folding-plates, these rods being connected to the plates 210 by means of screws passing through slots in the rods, thus permitting the connection between the rods 212 and plates 210 to be changed when the plates are adjusted longitudinally of the folding-plates 153.

The operation of the folding devices is as follows: The various operating-cams being timed to produce the proper movement of the parts which they operate, a blank having been fed to the folding devices and positioned with its bottom section directly beneath the forming-plunger, the plunger descends and clamps the bottom section of the blank between itself and the support 151. Then the plunger and support move downward together. As the central portion of the blank is thus carried downward the side sections are first bent upward by the side-folders 152 and the stay-flaps bent on the line of their connection with the side sections and caused to project inward above the end sections by

means of the flap-folders 154, which lie slightly within the line of the side-folders when the latter are in their retracted position. As the upper edges of the end-folders 153 lie slightly below the plane of the side-folders and flap-folders, the upward bending of the end sections will not begin until after the commencement of the folding of the side sections and stay-flaps. Figs. 44 and 45 show the positions of the side and end sections and stay-flaps when the forming plunger and support have been moved to carry the bottom portion of the box a slight distance downward. As the plunger and support move downward the side-folders 153 move inward and preferably complete their inward movement by the time the plunger and support reach the lowest point of their movement. As the plunger and support reach the lowest limit of their movement the end-folders 153 move inward to clamp the stay-flaps and end sections of the box together against the plunger. The movement of the side-folders should be completed before the end sections have made any substantial movement toward the plunger, so that the stay-flaps shall be in place before the end sections are pressed against them, as otherwise the contact of the pasted faces of the end sections with the stay-flaps would prevent the stay-flaps from being properly positioned and result in the production of an imperfect box. Fig. 46 shows the parts in position when the plunger and support have reached their lowest position and the end-folders have been moved in to clamp the ends and stay-flaps against the plunger. The plunger next begins to rise, the support 151 and the side and end folders remaining at rest, the box being prevented from rising with the plunger by shoulders 213, provided on the end-folders to project over the upper edge of the ends of the box. As the plunger rises the side folders are withdrawn, and as the bottom of the plunger reaches the top of the bed the end folders are withdrawn and the support 151 moves upward to its original position, as shown in Fig. 47, elevating the box and bringing it into position to be discharged.

To insure the ends of the box being clear of the shoulders 213 when the box is raised, clearing-fingers are preferably provided, formed by rods 214, mounted to extend through openings in the folders 153 and to project beyond the face of the folders when the latter are in their retracted position, as shown in Fig. 44. For making different-sized boxes, forming-plungers of the proper size will be secured to the rod 155, and the various folders will be adjusted to properly coact therewith.

After a box has been formed and elevated by the support 151, it may be discharged from the machine by any suitable discharg-

ing devices. I prefer, however, to provide for discharging the formed boxes a pair of discharging-belts which are moved into engagement with opposite sides of the boxes as the latter are successively elevated by the support 151, and which are supported with their inner or box-engaging runs moving in the direction of the movement of the blanks to the folding devices. I have shown in the drawings (see Figs. 1, 3, 6, and 41) a preferred construction for supporting and operating the discharging-belts. As here shown, each of the discharging-belts 220 is carried by grooved wheels 221, 222, mounted on a swinging frame 223, pivoted to a bracket 224. The brackets 224 are carried by a rod 225, hung from the frame 156, and are adjustable thereon for setting the swinging frames 222 toward or away from each other. The shafts of the belt-pulleys 221 are extended upward and connected by universal joints with the shafts of belt-pulleys 226, which are driven by belts 227 from a pulley 228, mounted on a bracket 229 on the rod 225, one of the belts 227 being crossed, so that the inner runs of the discharging-belts will move in the same direction. The pulley 228 is driven by a belt 230 from a pulley on a vertical shaft 231, which is driven by bevel-gear 232 from the shaft 14. The pulley 228 is adjustable on the bracket 229 for adjusting the tension of the belts 227 when the brackets 224 are moved to position the discharging-belts for different-size boxes. The swinging frames 223 are connected by rods 233 and 234 to the opposite ends of a cross-arm 235 on a vertical shaft 236, which is rocked to intermittently swing the frames 223 to carry the discharging-belts toward each other and against the box to be discharged by a cam 237 on the shaft 231, acting through an arm 238 on said shaft 236. The discharging-belts are thus continuously driven, so that their inner runs move in the direction of the arrows in Figs. 1 and 40, and at the proper times, when a box has been made and elevated by the support 151, the frames 223 are swung inward to bring the inner runs of the discharge-belts into contact with the opposite sides of the box, and the box is thereby moved horizontally from the support 151.

Any suitable receiving means may be provided for receiving the boxes from the discharging-belts; but I preferably provide a receiving-apron 240, mounted on rolls 241 and 242 and driven by means of a sprocket-chain 243, running over sprocket-wheels on the shaft 14 and the shaft of the roll 241, respectively. The boxes will thus be delivered by the discharging-belts to the apron 240, from which they may be taken by hand or by which they may be discharged into a suitable receptacle or otherwise disposed of. Supports 245, having downwardly-inclined ends, are preferably provided, extending over the

edge of the table 177 into the opening 178 to prevent the bottom of the boxes from coming into contact with the edge of the table as they are advanced by the discharge-belts. As the blanks are advanced by the feeding-tapes 135 into position for being folded they bring up against stop-pins 250, by which their further movement is prevented when they have been advanced the proper distance beneath the forming-plunger. The stops 250 are adjustable for blanks of different sizes and for this purpose are carried by arms 251, pivotally mounted and secured by set-screws 252 on slotted bars 253, which are secured to the table 177 by means of screws, as shown in Figs. 29 and 32.

In order to secure the accurate positioning of the blanks with relation to the folding devices transversely of their movement to the folding devices, I preferably provide a stationary gage 255, in position to be engaged by one end edge of the blank when the latter is in proper position with relation to the folding devices, and a reciprocating gage or pusher 256, mounted to reciprocate transversely of the direction of the movement of the blank to the folding devices and given a quick reciprocation to engage the other end edge of the blank and move the blank laterally of the direction of its movement to the folding devices to bring its opposite end edge into engagement with the gage 255. The feeding and pasting devices are preferably adjusted so that the blanks will be fed to the folding devices slightly out of register therewith laterally, so as to move clear of the stationary gage 255 as they are advanced to the stops 250. As shown, the pusher 256 is carried by bars 257, mounted to slide in grooves 258 in the table 177 and connected by a cross-piece 259, which carries a bar 260, which is pivotally connected to one end of a lever 261, the other end of which carries an antifriction-roll in position to be engaged by a revolving finger 262 on a shaft 231. The pusher 256 is normally held retracted by means of a spring 263, acting to hold the lever 261 against a stop 264; but at each rotation of the shaft 231 the finger 262 will throw the lever 261 and cause the pusher 256 to be moved quickly forward and then allow it to be immediately returned by the spring 263. The cross-piece 259 has an adjustable connection with the rods 257, as by means of the slots and screws, as shown in Fig. 29, and the lever 261 may also be adjustably connected to the arm 260, as shown, thus providing for the ready adjustment of the pusher 256 for blanks of different sizes. The gage 255 is carried by rods 265, adjustable in grooves 266 in the table 177 by means of slots in the rods and screws, as shown in Fig. 29. The gages 255 and 256 may be of any suitable form; but I have shown them as each formed by means of two engaging plates 267, adjustable toward and

- from each other on bars 268, carried by the sliding bars 257 257 and 265 265, respectively. A blank being advanced to the folding devices by the tapes 135 is stopped by the 5 stop-pins 250 when it has been carried into position longitudinally of the direction of its movement and is positioned transversely to the direction of its movement by the quick forward reciprocation of the pusher 256.
- 10 To insure the blank being properly positioned longitudinally of the direction of its movement against the stops 250, means are preferably provided in addition to the feeding-tapes 135 for engaging the blanks as they 15 approach the stops to move them against the stops. For this purpose there is preferably provided a swinging gage or pusher formed by fingers 270, carried by a rock-shaft 271, positioned and operated so that the fingers 20 270 will lie above the path of the blanks and as a blank passes beneath them to the folding devices will swing to engage the rearward edge of the blank and force the blank against the stops 250. As shown, the fingers are 25 normally held in their retracted position by a spring 272, and the shaft 271 is rocked against the tension of the spring to give the fingers their positioning movement by means of a two-armed lever 273, one arm of which is 30 connected, as by a chain 274, with an arm on the shaft 271 and the other arm of which lever is connected by a chain 275 to one arm of a bell-crank lever 276, the other arm of which is connected by a chain 277 to the 35 cross-bar 259, which connects the bars 257, carrying the pusher 256. The fingers 270 will thus act to position the blank against the stops 250 at the same time that it is positioned against the gage 255 by the pusher 256. To provide for adjusting the fingers 270 for blanks of different sizes, the shaft 271 40 is preferably carried by arms 278, having a sliding adjustment on brackets 279, rotatably adjustable on a shaft 280. The fingers 45 270 are also preferably adjustable longitudinally on the shaft 271.
- The operation of the machine as a whole will be understood from the foregoing description and need not be further set out.
- 50 It will be understood that the term "box" is used broadly herein to include either the body or bottom portion of a box and box-cover, and by the term "bottom section" is meant the central section of the blank 55 which forms the bottom of a box-body or the top of a cover. By the term "side sections" is meant the sections of the blanks which carry the stay-flaps and by "end sections" the other sections attached to the bottom section, and the "ends" of the box, as the term 60 is used herein, are the sides formed by the end sections and the stay-flaps of the blank, and the sides of the box are the sides formed by the side sections of the blank.
- 65 By my invention I provide a machine of

high capacity and efficiency by which blanks may be fed, pasted, and folded to form the boxes and the formed boxes rapidly delivered, the feeding devices acting with sureness and the folding devices acting to 70 accurately form the boxes, bringing the various parts accurately into position and exerting sufficient pressure on the surfaces to be secured together by the paste to cause them to properly adhere to each other, and 75 the various parts of the machine all being readily adjustable for operating on blanks of different sizes and proportions.

It will be understood that I am not to be limited to the exact construction or arrangement and combinations of parts of the machine as shown in the drawings, and to which the foregoing description has been mainly confined, but that changes therein may be made within the claims and that portions 85 of the machine may be used without other portions thereof or in connection with other machines or parts of machines.

What is claimed is—

1. The combination of feeding devices for 90 feeding material to be pasted, a paster, a support coöperating therewith, separating means for moving one of said members away from the other, means for actuating said separating means, a detector-finger adapted to be 95 engaged by the material as it advances to the paster, and devices controlled by the detector-finger for causing the separating means to be actuated by the actuating means, substantially as described.

2. The combination of feeding devices for feeding material to be pasted, a rotary paster, a support coöperating therewith, separating means for moving the paster away from the support without interrupting its rotation, 105 means for actuating said separating means, a detector-finger adapted to be engaged by the material as it advances to the pasting-roll, and devices controlled by the detector-finger for causing the separating means to be 110 actuated by the actuating means, substantially as described.

3. The combination of feeding devices for feeding material to be pasted, a paster, a support coöperating therewith, means for 115 moving one of said members away from the other, a stop for preventing the operation of said means, releasing devices for withdrawing said stop to permit said means to operate, and a detector-finger for controlling the 120 operation of said releasing devices adapted to be engaged by the material as it advances to the paster, substantially as described.

4. The combination of feeding devices for feeding material to be pasted, a rotary paster, a support coöperating therewith, means for moving one of said members away from the other, a stop for preventing the operation of said means, releasing devices for withdrawing 125 said stop to permit said means to operate,

ate, a detector-finger for controlling the operation of said releasing devices adapted to be engaged by the material as it advances to the paster, and means for returning the parts to 5 pasting position at will, substantially as described.

5. The combination of a blank-holder, means for advancing blanks successively from the holder, a rotary paster, a support 10 co-operating therewith, means for moving one of said members away from the other, a stop for preventing the operation of said means, releasing devices for withdrawing said stop to permit said means to operate, a detector-finger for controlling the operation of said 15 releasing devices adapted to be engaged by the material as it advances to the paster, and means for returning the parts to pasting position at will, substantially as described.

20 6. The combination of feeding devices for advancing material to be pasted, pasting mechanism, means for controlling the pasting mechanism to prevent the application of paste by the paster to other parts of the machine when no material is in position to be pasted, a stop for preventing the operation of said means, releasing devices for withdrawing said stop to permit said means to operate, and a detector-finger for controlling 25 30 the operation of said releasing devices adapted to be engaged by the material as it advances to the pasting mechanism, substantially as described.

7. The combination of feeding devices for advancing material to be pasted, pasting mechanism, means for controlling the pasting mechanism to prevent the application of paste by the paster to other parts of the machine when no material is in position to be 35 pasted, a stop for preventing the operation of said means, a moving member, connecting devices for connecting said member with said stop, and a detector-finger for controlling said connecting devices adapted to be 40 45 engaged by the material as it advances to the pasting mechanism, substantially as described.

8. The combination of feeding devices for advancing material to be pasted, pasting mechanism, means for controlling the pasting mechanism to prevent the application of paste by the paster to other parts of the machine when no material is in position to be pasted, a stop for preventing the operation 50 of said means, an intermittently-reciprocating member, connecting devices for connecting said member with said stop, and a detector-finger for controlling said connecting devices adapted to be engaged by the material as it advances to the pasting mechanism, substantially as described.

60 9. The combination of feeding devices for advancing the material to be pasted, pasting mechanism, means for controlling the pasting mechanism to prevent the application of

paste by the paster to other parts of the machine when no material is in position to be pasted, a stop for preventing the operation of said means, a detector-finger adapted to be engaged by the material as it advances to 70 the pasting mechanism, an intermittently-reciprocating member, a part connected with the stop, and a part controlled by the detector-finger and arranged to be projected between said member and said part when no 75 material is being advanced to the pasting mechanism, substantially as described.

10. The combination of the rock-shaft 109, means for intermittently rocking said shaft, finger 115 fast on said shaft, stop-arm 80 108 loosely mounted on said shaft, finger 114 carried by the stop-arm 108 and projecting in proximity to the finger 115, detector-finger 117, lever 119 connected with the detector-finger 117 and having a lug 121 adapted 85 to be projected between the fingers 114 and 115, substantially as described.

11. The combination of an intermittently-reciprocating member, a stop-arm having a part projecting in proximity to said member, 90 a detector-finger 117, a lever 119 having a slotted pivotal connection with its support and with the detector-finger 117 and having a part adapted to be projected between the reciprocating member and the part carried 95 by the stop-arm, substantially as described.

12. The combination of means for advancing blanks successively to be pasted, pasting mechanism, means for controlling the pasting mechanism to prevent the application of paste by the paster to other parts of the machine when no blank is in position to be pasted, a stop for preventing the operation of said means, a member moving in time with the feeding of the blanks, connecting devices 100 for connecting said member with said stop, and a detector-finger for controlling said connecting devices adapted to be engaged by the blanks as they are advanced to the pasting mechanism, substantially as described. 105

13. The combination of means for advancing blanks successively to be pasted, a rotary paster, a support co-operating therewith, means for moving one of said members away from the other, a stop for preventing the operation of said means, releasing devices for withdrawing said stop to permit said means to operate, said releasing devices including a member moving in time with the feeding of the blanks, and a detector-finger for controlling 110 the operation of said releasing devices adapted to be engaged by the blanks as they are advanced to the paster, substantially as described.

14. The combination of means for advancing blanks successively to be pasted, a rotary paster, a support co-operating therewith, means for moving one of said members away from the other, devices for controlling the operation of said means including a member 115 120 125

moving in time with the feeding of the blanks, and a detector-finger for controlling the operation of said devices adapted to be engaged by the blanks as they advance to the paster, substantially as described.

15. The combination of a rotary paster, a support coöperating therewith, rotary journal-blocks 100 in which the shaft of the paster is eccentrically journaled, means for rotating said journal-blocks to move the paster away from the support, and means controlled by the material to be pasted for preventing the operation of said means for moving the paster, substantially as described.

16. The combination of means for advancing material to be pasted, a pasting-cylinder, securing means for attaching to the surface of the cylinder pasting-surfaces of different sizes and in different positions, a support coöperating with the pasting-surfaces, a vibrating transfer-roll for applying paste to the pasting-surfaces, and means for vibrating the transfer-roll adjustable for varying the time of vibration of said roll and for holding it in the paste-applying position for a longer or shorter period, substantially as described.

17. The combination of means for advancing material to be pasted, a pasting-cylinder adapted to carry pasting-surfaces of different sizes, a vibrating transfer-roll for applying paste to the pasting-surfaces, and means for vibrating the transfer-roll adjustable for holding it in the paste-applying position for a longer or shorter period, substantially as described.

18. The combination of means for advancing separate blanks successively to be pasted, a rotary paster, a series of supporting-rolls on which the blanks pass the paster, feeding-rolls coöperating with one or more of the supporting-rolls, folding devices, and feeding devices including a pair of feeding-rolls beyond the supporting-rolls for advancing the blanks to the folding devices at an accelerated speed, substantially as described.

19. The combination of means for advancing separate blanks successively to be pasted, pasting devices, folding devices, and feeding devices for advancing the blanks from the pasting devices to the folding devices at a speed greater than the speed at which they are advanced to and past the pasting devices, substantially as described.

20. The combination of a holder for blanks, pasting devices, means for advancing the blanks successively from the holder to the pasting devices, folding devices, and feeding devices for advancing the blanks from the pasting devices to the folding devices at a speed greater than the speed at which they are advanced from the holder to the pasting devices, substantially as described.

21. The combination of a holder for blanks, means for advancing the blanks successively from the holder, folding devices, and feeding

devices for advancing the blanks to the folding devices with a speed greater than the speed at which they are advanced from the holder, substantially as described.

22. The combination of means for advancing separate blanks successively to be pasted, pasting devices, folding devices, rolls for advancing the pasted blanks at a speed greater than the speed at which they are advanced to the pasting devices, and feeding-tapes moving at such accelerated speed for carrying the blanks from the feeding-rolls to the folding devices, substantially as described.

23. The combination of blank-folding devices, feeding devices for advancing the blanks to the folding devices, a stop for limiting the movement of the blanks, a pusher lying normally out of the path of the blanks, and means for moving said pusher transversely of and in the direction of movement of the blanks for engaging the rearward edge of the blanks to force them against the stop, substantially as described.

24. The combination of blank-folding devices, feeding-tapes for advancing the blanks to the folding devices, a stop for limiting the movement of the blanks, a pusher lying normally out of the path of the blanks, and means for moving said pusher transversely of and in the direction of movement of the blanks for engaging the rearward edge of the blanks to force them against the stop, substantially described.

25. The combination of blank-folding devices, feeding devices for advancing the blanks to the folding devices, a stop for limiting the movement of the blanks, and a swinging pusher for engaging the rearward edge of the blanks to force them against the stop, substantially as described.

26. The combination of blank-folding devices, feeding devices for advancing the blanks to the folding devices, a stop for limiting the movement of the blanks, a swinging pusher for engaging the rearward edge of the blanks to force them against the stop, and means for adjusting the stop and pusher for different-sized blanks, substantially as described.

27. The combination of blank-folding devices, feeding devices for advancing the blanks to the folding devices, a stop for limiting the movement of the blanks, and a swinging pusher mounted on a horizontal shaft above the path of the blanks for engaging the rearward edge of the blanks to force them against the stop, substantially as described.

28. The combination of blank-folding devices, stops for engaging adjacent edges of the blank to determine its position with relation to the folding devices, and pushers for engaging the opposite edges of the blank, one of said pushers being pivotally mounted on a horizontal shaft located in a plane above the plane in which the blanks are positioned with

relation to the folding devices to permit the blank to be fed to the folding devices beneath said pusher, substantially as described.

29. The combination of blank-folding devices, stops for engaging adjacent edges of the blank to determine its position with relation to the folding devices, a reciprocating pusher for engaging the edge of the blank opposite to the edge engaged by one of the stops, and a swinging pusher for engaging the edge of the blank opposite to the edge engaged by the other of the stops, substantially as described.

30. The combination of blank-folding devices, feeding devices for advancing the blanks to the folding devices, a stop for limiting the movement of the blanks, and positioning devices for positioning the blanks transversely of the direction of their movement to the folding devices, substantially as described.

31. The combination of blank-folding devices, feeding devices for advancing the blanks to the folding devices, and a reciprocating pusher for positioning the blanks transversely of the direction of their movement to the folding devices, substantially as described.

32. The combination of blank-folding devices, feeding devices for advancing the blanks to the folding devices, means for determining the position of the blanks longitudinally of the direction of their feeding movement, and a stop and a reciprocating pusher for engaging opposite edges of the blanks to position them transversely of the direction of their movement to the folding devices, substantially as described.

33. The combination of blank-folding devices, feeding devices for advancing the blanks to the folding devices, a stop for limiting the movement of the blanks, a pusher for engaging the rear end of the blanks held normally out of the path of the blanks, and a stop and a reciprocating pusher for engaging opposite edges of the blanks to position the blanks transversely of the direction of their movement to the folding devices, substantially as described.

34. In a box-making machine, the combination of a reciprocating former, side and end folders between which the blank is carried by the former, a reciprocating support, and means for operating the support to deliver the formed box from between the folders after the former has been withdrawn from the box, substantially as described.

35. In a box-making machine, the combination of a reciprocating former, side and end folders between which the blank is carried by the former, a reciprocating support, and means for operating the support to clamp the bottom section of the blank to the former during the folding operation and to deliver the formed box from between the

folders after the former has been retracted therefrom, substantially as described.

36. In a box-making machine, the combination of a former, side and end folders coöperating with the former to fold the blank, means for causing a separating movement between the former and the folders for retracting the former from the box, a reciprocating support for delivering the box from between the folders after the former has been retracted therefrom, substantially as described.

37. In a box-making machine, the combination of a former, side and end folders coöperating with the former to fold the blank, means for causing a separating movement between the former and the folders for retracting the former from the box, retaining-shoulders for stripping the box from the former, and means for delivering the formed box from between the folders past the retaining-shoulders, substantially as described.

38. In a box-making machine, the combination of a reciprocating former, side and end folders, retaining-shoulders for stripping the box from the former, and means for delivering the box from between said folders past the retaining-shoulders, substantially as described.

39. In a box-making machine, the combination of a reciprocating former, side and end folders between which the blank is carried by the former, retaining-shoulders for stripping the box from the former, means for clearing the box from the retaining-shoulders, and means for delivering the box from between the folders past the retaining-shoulders, substantially as described.

40. In a box-making machine, the combination of a reciprocating former, side and end folders between which the blank is carried by the former and one pair of said folders having a reciprocating movement toward and away from the former, retaining-shoulders on the reciprocating folders for stripping the box from the former, clearers adapted to project beyond said folders when the reciprocating folders are retracted, and a reciprocating support for delivering the box from between the folders, substantially as described.

41. In a box-making machine, the combination of a former, side and end folders coöperating with the former to fold the blank, means for causing a separating movement between the former and the folders for retracting the former from the box, retaining-shoulders for stripping the box from the former, and means for clearing the box from the retaining-shoulders to permit the box to be delivered from between the folders past the retaining-shoulders, substantially as described.

42. In a box-making machine, the combination of a former, side and end folders coöp-

- erating with the former to fold the blank and one pair of said folders having a reciprocating movement toward and away from the former, retaining-shoulders on the reciprocating folders for stripping the box from the former, and clearers adapted to project beyond said shoulders when the reciprocating folders are retracted, substantially as described.
43. In a box-making machine, the combination of a former, reciprocating folders co-operating with the former to fold the blank, retaining-shoulders on said folders for stripping the box from the former, and clearers adapted to project beyond said shoulders when the folders are retracted, substantially as described.
44. In a box-making machine, the combination of a former, reciprocating folders co-operating with the former to fold the blank, retaining-shoulders on said folders for stripping the box from the former, and stationary clearers extending through openings in the folders to project beyond said shoulders when the folders are retracted, substantially as described.
45. In a machine for making boxes from blanks having bottom sections *a*, side sections *c*, end sections *b* and stay-flaps *d* extending from the ends of the side sections, the combination of a former, side-folders for folding the side sections of the blank against the former, reciprocating end-folders for folding the end sections of the blank against the former, and stay-flap folders adjustably mounted on the end-folders and adapted to fold the stay-flaps inside the end sections, substantially as described.
46. In a machine for making boxes from blanks having bottom section *a*, side sections *c*, end sections *b* and stay-flaps *d* extending from the ends of the side sections, the combination of a former, side-folders for folding the side sections of the blank against the former, end-folders for folding the end sections of the blank against the former, and stay-flap folders mounted on the end-folders and projecting above and inward beyond the end-folders, for folding the stay-flaps inside the end sections substantially as described.
47. In a machine for making boxes from blanks having bottom section *a*, side sections *c*, end sections *b* and stay-flaps *d* extending from the ends of the side sections, the combination of a former, side-folders for folding the side sections of the blank against the former, reciprocating end-folders for folding the end sections of the blank against the former, stay-flap folders mounted on the end-folders and adapted to fold the stay-flaps inside the end sections, and means for adjusting the stay-flap folders longitudinally of the end-folders, substantially as described.
48. In a machine for making boxes from blanks having bottom section *a*, side sections

c, end sections *b* and stay-flaps *d* extending from the ends of the side sections, the combination of a former, side-folders for folding the side sections of the blank against the former, reciprocating end-folders for folding the end sections of the blank against the former, stay-flap folders mounted on the end-folders and adapted to fold the stay-flaps inside the end sections, and means for adjusting the stay-flap folders to project a greater or less distance inward beyond the end-folders, substantially as described.

49. In a machine for making boxes from blanks having bottom section *a*, side sections *c*, end sections *b* and stay-flaps *d* extending from the ends of the side sections, the combination of a former, side-folders for folding the side sections of the blank against the former, reciprocating end-folders for folding the end sections of the blank against the former, means for adjusting the side-folders and the end-folders for co-operating with formers of different sizes, stay-flap folders mounted on the end-folders and adapted to fold the stay-flaps inside the end sections, and means for adjusting the stay-flap folders longitudinally of the end-folders, substantially as described.

50. In a machine for making boxes from blanks having bottom section *a*, side sections *c*, end sections *b* and stay-flaps *d* extending from the ends of the side sections, the combination of a former, reciprocating side-folders for folding the side sections of the blank against the former, reciprocating end-folders for folding the end sections of the blank against the former, means for adjusting the side-folders and the end-folders for co-operating with formers of different sizes, stay-flap folders mounted on the end-folders and adapted to fold the stay-flaps inside the end sections, and means for adjusting the stay-flap folders longitudinally of the end-folders, substantially as described.

51. In a machine for making boxes from blanks having bottom section *a*, side sections *c*, end sections *b* and stay-flaps *d* extending from the ends of the side sections, the combination of a reciprocating former, side-folders for folding the side sections of the blank against the former, reciprocating end-folders for folding the end sections of the blank against the former, stay-flap folders mounted on the end-folders, and a reciprocating support actuated to clamp the bottom section of the blank against the former and to move downward with the former, substantially as described.

52. In a machine for making boxes from blanks having bottom section *a*, side sections *c*, end sections *b* and stay-flaps *d* extending from the ends of the side sections, the combination of a reciprocating former, side-folders for folding the side sections of the blank against the former, reciprocating end-folders

for folding the end sections of the blank against the former, stay-flap folders mounted on the end-folders, a reciprocating support actuated to clamp the bottom section of the 5 blank against the former and to move downward with the former, feeding devices for advancing blanks beneath the former, and positioning devices for positioning the blanks 10 transversely of the direction of their movement to the folding devices, substantially as described.

53. In a machine for making boxes, the combination of a reciprocating former, side and end folders, a support for raising the 15 formed box above the folders, and discharging devices independent of the folders for engaging opposite sides of the box to carry the box from the forming devices longitudinally of the engaged sides and transversely to the 20 direction in which the box is moved by the support, substantially as described.

54. In a machine for making boxes, the combination of a reciprocating former, side and end folders, a support for raising the 25 formed box above the side and end folders, and discharging-belts for engaging opposite sides of the box to move it from the folding devices transversely to the direction in which the box is moved by the support, substantially 30 as described.

55. In a machine for making boxes, the combination with folding devices comprising side and end folders for folding a blank to form a box, of means for moving the formed 35 box from between the side and end folders, a discharging-belt for engaging opposite sides of the box to move it from the folding devices transversely to the direction of such movement of the box from between the side and 40 end folders, substantially as described.

56. In a machine for making boxes, the combination with folding devices for folding a blank to form a box, of a pair of discharging-belts, and means for moving the belts toward 45 each other to engage opposite sides of the box to move it from the folding devices, substantially as described.

57. In a machine for making boxes, the combination of a reciprocating former, side 50 and end folders, a support for raising the formed box above the side and end folders, discharging-belts on opposite sides of the path of the former and mounted to move toward and from each other, means for holding 55 the belts normally retracted away from the path of the former and for moving them toward each other to engage the box to move it from the folding devices, substantially as described.

60. 58. In a machine for forming boxes, the combination with folding devices for folding a blank to form a box, of a discharging-belt, means for moving the discharging-belt clear

of the folding devices during the folding operation and for moving it into position to 65 engage the box after the completion of the folding operation, substantially as described.

59. In a machine for making boxes, the combination with folding devices for folding a blank to form a box, of a pair of discharging-belts, swinging frames on which the belt-pulleys are mounted, and means for swinging 70 said frames to cause the belts to approach each other to engage the box, substantially as described.

60. In a machine for making boxes, the combination with folding devices for folding a blank to form a box, of discharging-belts 75 200 carried by swinging frames 223, brackets by which the swinging frames are pivotally supported, adjustable toward and away from each other, means for driving the belts including an adjustable pulley 228, and means for swinging the frames to cause the belts to approach each other to engage the box, substantially 80 as described.

61. In a machine for making boxes, the combination with folding devices for folding a blank to form a box, of discharging-belts 90 220 carried by swinging frames 223, adjustable brackets 222 by which the swinging frames are pivotally supported, adjustable driving-pulley 228, belt-pulleys 226 on shafts mounted in the brackets 224, and the belt-driving pulleys 221 carried by shafts journaled in the swinging frames 223 and having a universal connection with the shafts of the pulleys 226, and means for swinging the frames 223 to cause the belts to approach each other to engage the box, substantially 95 as described.

62. In a machine for making boxes, the combination with the folding devices for folding a blank to form a box, of a pair of discharging-belts, means for moving the belts 105 toward each other to engage the box, and a discharging-apron for receiving the boxes from the belts, substantially as described.

63. In a machine for making boxes, the combination with the reciprocating former 110 and a reciprocating support coöperating with the former during the folding operation, of means for reciprocating said members, and adjustable connections between said means and said members for varying the amount of 115 the movement of said members and the relative positions of said members, substantially as described.

In testimony whereof I have hereunto set my hand in the presence of two subscribing 120 witnesses

FRED R. HARRIS.
